UNITED STATES PATENT OFFICE.

SERGE DE KAZARINE AND MARY DE POROHOVCHIKOVA, OF LONDON, ENGLAND.

DESIGN FOR A DRESSED DOLL.

59,514.

Specification for Design.

Patented Oct. 25, 1921.

Application filed January 13, 1920. Serial No. 351,265. Term of patent 14 years.

To all whom it may concern:

Be it known that we, SERGE DE KAZARINE and MARY DE POROHOVCHIKOVA, citizens of Russia, and residing at London, England, have invented a new, original, and ornamental Design for a Dressed Doll, of which the following is a specification, reference being had to the accompanying drawing, forming part thereof.

The drawing is an elevation of a dressed doll showing our new design.

We claim:

The ornamental design for a dressed doll as shown.

In testimony whereof we have signed our names to this specification.

SERGE DE KAZARINE.

MARY DE POROHOVCHIKOVA.
